UNITED STATES PATENT OFFICE

ANNE M. BOEVER, OF CAMBRIDGE, MASSACHUSETTS, ASSIGNOR TO THE SILEX COMPANY, A CORPORATION OF CONNECTICUT

DESIGN FOR A COFFEE MAKER

Application filed July 16, 1928. Serial No. 27,494. Term of patent 14 years.

To all whom it may concern:

Be it known that I, ANNE M. BOEVER, a citizen of the United States, residing at Cambridge, in the county of Middlesex and State of Massachusetts, have invented a new, original, and ornamental Design for Coffee Makers, of which the following is a specification, reference being had to the accompanying drawings, forming part thereof.

In these drawings,—

Fig. 2 is a plan view of the same.

I claim:—

The ornamental design for a coffee maker, substantially as shown.

In testimony whereof I affix my signature.

ANNE M. BOEVER.

CERTIFICATE OF CORRECTION.

Design Patent No. 80,014.

Granted December 3, 1929, to

ANNE M. BOEVER.

It is hereby certified that error appears in the above numbered patent requiring correction as follows: In the drawing, Figures 1 and 2, should appear as shown below instead of as in the present drawing of the patent;

Fig. 2.

Fig. 1.

and that the said Letters Patent should be read with this correction therein that the same may conform to the record of the case in the Patent Office.

Signed and sealed this 7th day of January, A. D. 1930.

M. J. Moore,
Acting Commissioner of Patents.
